Primary Examiner—Ted Shooman*Assistant Examiner*—C. Tuttle*Attorney, Agent, or Firm*—McCormick, Paulding & Huber[57] **CLAIM**

The ornamental design for a razor handle, as shown and described.

DESCRIPTION

FIG. 1 is a right side elevational view of a razor handle showing my new design, the left side being a mirror image of the side shown;

FIG. 2 is a top plan view thereof;

FIG. 3 is a bottom plan view thereof;

FIG. 4 is a front elevational view of the handle shown on an enlarged scale; and,

FIG. 5 is a rear view thereof.

The broken line showing of the razor is for illustrative purposes only and forms no part of the claimed design.
